UNITED STATES PATENT OFFICE

WINFRED M. BROOKS, OF WEST ORANGE, NEW JERSEY

CLOSURE

Application filed April 2, 1931. Serial No. 527,139.

The present invention relates generally to closures, and has for its main object and feature the provision of means to afford a reliable and inexpensive sealing medium to be associated with a sheet-material cap employed in connection with an open-mouth container, such as a milk bottle.

In the accompanying drawings the invention is disclosed in a concrete and preferred form in which:

Fig. 1 is a view in elevation of a device embodying the invention;

Fig. 2 is a vertical sectional view substantially on the plane of line 2—2 of Fig. 1; and
15 Fig. 3 is a horizontal sectional view substantially on the plane of line 3—3 of Figs. 1 or 2.

1 indicates an open-mouth container, here a milk bottle, having a neck-portion 2 provided with a circumferential ledge 3 above which are screw-threads. 4 is a cap of sheet material having threads 5 to engage the threads of the neck of the bottle, and having also a closed top 6 and a circumferential bead 7 below the threads. When this cap is screwed on the neck of the bottle, bead 7 is located just above ledge 3 of the bottle. 8 is a sealing element of sheet material adapted to surround the neck of the bottle and is provided with a circumferential groove 9 to receive bead 7. Said element is further provided with an upper and a lower flange 10 and 11. Flange 10 is adapted to extend over the top of the cap, and flange 11 to engage beneath ledge 3. Suitable means such as bolt 12 connects the free ends 13 of the sealing element.

It will be seen that by the construction above described, it is possible to have flanges 10 and 11 of very narrow width without sacrificing a proper grip on the bottle, because groove 9 is in intimate engagement with bead 7. Not only does this lessen the amount of metal required and therefore cuts down expense, but it also avoids the difficulty encountered when it is attempted to draw the metal to provide relatively wide flanges in place of narrow flanges 10 and 11, said difficulty consisting in the material curling radially to compensate for the decrease in diam-

eter occasioned by the formation of the flanges.

I claim:

The combination of an open mouth container having a threaded portion adjacent its open mouth and, below said portion, a circumferential ledge; a sheet-material cap, for the open mouth, located above the ledge and provided with a top, a threaded portion to engage the threaded portion of the container, and a circumferential bead at its lower end adjacent the ledge; and a sealing element, to enclose the cap and ledge, provided with an intermediate circumferential groove to receive the bead on the cap and having an upper and a lower flange, the former to extend over the top of the cap and the latter to engage beneath the ledge.

Signed at New York, in the county of New York, and State of New York, this 23rd day of March, 1931.

WINFRED M. BROOKS.
